UNITED STATES PATENT OFFICE.

CHARLES HOFMANN, OF CHICAGO, ILLINOIS.

DESIGN FOR A SIGN AND HAT-RACK.

SPECIFICATION forming part of Design No. 25,948, dated August 18, 1896.

Application filed June 25, 1896. Serial No. 596,946. Term of patent 3½ years.

To all whom it may concern:

Be it known that I, CHARLES HOFMANN, a citizen of the United States, residing at No. 1236 West Fifteenth street, in the city of Chicago, in the county of Cook and State of Illinois, have invented and produced a new and original Design for a Sign and Hat-Rack, of which the following is a specification, reference being had to the accompanying drawing, showing the full front view.

The leading feature of my design consists in the figure of a newsboy A running, with the newspapers B held out in his left hand, the whole character and expression of the figure, together with the extended newspaper, representing the idea of an announcement of very important news. The full page C of the extended newspaper provides a prominent place for advertising purposes. All this appears as the relief ornament of a peculiarly-

shaped shield D, with a crown E as a head-piece, and adorned all over its surface in appropriate places by artistically-curved lines or garlands. At the upper right and left extremes the corners, gracefully curved, leave 25 apertures F. A similar curve and aperture is made at the center of the lowest edge of the ornament, through each of which apertures, three in number, ornamental projections may be screwed into the door, wall, 30 partition, or other fixture, thus fastening the sign and furnishing a handsome and novel hat-rack.

What I claim is—

The design for a combination sign and hat-rack as herein shown and described.

CHARLES HOFMANN.
